UNITED STATES PATENT OFFICE.

GEORGE P. PIERCE, OF KANSAS CITY, MISSOURI.

SILO-DOOR.

1,311,357.

Specification of Letters Patent. Patented July 29, 1919.

Application filed May 22, 1917. Serial No. 170,297.

To all whom it may concern:

Be it known that I, GEORGE P. PIERCE, a citizen of the United States, residing at Kansas City, in the county of Jackson and 5 State of Missouri, have invented certain new and useful Improvements in Silo-Doors, of which the following is a specification.

This invention relates to silo doors and aims particularly to provide a structure 10 wherein the door may be closely sealed in connection with the door frame during the normal operation of closing the same.

Primarily, my invention resides in the combination of a door frame concaved to suit 15 the curvature of the silo, with a flexible door adapted to be drawn into closing engagement with the frame. A further provision resides in a structure whereby this door is drawn toward the door frame from along its 20 edges, thus causing it to assume the contour of the frame by drawing the outer portions toward the center, which would naturally cause the door itself to bulge and this is resisted by the shape of the frame. In this 25 manner, the door opening may be very conveniently sealed.

A further object of the invention resides in a structure for attaching the reinforcing rod to the door frame. This structure is 30 particularly adaptable to tile silos wherein the reinforcing rod is located between the inner and outer faces of the tile sections.

The preferred embodiment of my invention 35 is shown in the accompanying sheet of drawings, in which similar characters of reference designate corresponding parts, and in which:

Figure 1 is a face view of my improved type of door,

40 Fig. 2 is a section taken on line 2—2 of Fig. 1,

Fig. 3 is a view in perspective showing the manner in which the reinforcing rod is anchored to the door frame, and,

45 Fig. 4 is a section taken on line 4—4 of Fig. 2.

In these drawings, the door frame is designated in its entirety by the reference numeral 1. This frame is preferably of a unitary rigid construction whose legs are preferably U-shaped as is shown. This door is particularly adapted for use in connection with tile or cement stave silos, although it is not limited to such use. The one piece 55 nature of the door frame is desirable in that I have provided means for anchoring

the ends of the reinforcing rods 2 thereto, by means of the anchor clip 3, shown in detail in Fig. 3. This clip is adjustably carried by the frame by means of the bolt and 60 nut structure shown at 4 operating within the slot 5. By means of this, the clips may be adjusted vertically as may be desired to be properly located with respect to the reinforcing rods 2 which are usually located 65 between and within the mortar joints. The opposite leg of the anchor clip 3 is also provided with a slot shown at 6 wherein the downturned end 7 of the reinforcing rod 70 is located.

The door frame itself is placed vertically within the silo structure, but is curved slightly to fit the general contour of the silo, as is shown in Fig. 2. The door 8 for closing the frame opening is of a size slightly 75 larger than the opening within the frame and is itself of slightly flexible material. Along opposite edges I have located a reinforcement in the form of an angle 9. It is by means of these angles that the door is 80 maintained rigid as regards its longitudinal direction and it is also by means of these angles and the truss bars 10, that the door is caused to bulge transversely to assume the contour of the door frame. The truss bars 85 are each shaped as shown in Fig. 2 and are secured in the upper and lower ends of the reinforcement angles 9 by bending down their ends as is shown at 11. At approximately the center of each, there is provided 90 a head portion 12, which is drilled and tapped to receive the threaded end of the eye bolts 13. The heads 14 of these bolts operate in connection with clips 15 and 16 respectively, carried by the ladder rungs 17 95 and 18. It will be understood that these clips 15 and 16 are secured in permanent relation with the door frame, but inasmuch as ladder rungs are necessary in silo construction, I have attached these rungs directly to the door frame and supported the 100 clips therefrom. The clip 15 is provided with a downwardly projecting slot 19 in which the head 14 of the upper bolt operates and this clip is rigidly secured to the ladder 105 rung, while the clip 16 is pivotally secured to its ladder rung 18, as is shown at 20 and is provided with a laterally projecting slot 21. This arrangement is resorted to in order to permit the clip 16 swinging out of interfering position after the door has been 110 removed.

Inasmuch as the two truss bars 10 are operatively connected with the flexible door 8 adjacent its vertical edges, a pulling action along these edges, will cause this door 5 to buckle from the center and in so doing, will make it conform to the exact shape of the door frame itself. To accomplish this, the operator causes the heads of the bolts 13 to engage the clips 15 and 16 and then by 10 rotating these bolts, the truss bars 10 are drawn outwardly which is permitted by their inherent resiliency and by so doing, the edges of the doors are pulled toward the door frame and at the same time the center 15 bulges to cause a tight sealing engagement between the door and frame. The angle clips 3 are adjusted to the desired position while the silo is being built, to enable the reinforcing rods 2 to be secured in position 20 and, because of the unitary nature of the door frames, these frames virtually form a continuation of the reinforcing rods.

What I claim is:

1. In a silo, an arcuately shaped door frame, a flexible door, and means for locking said door in said frame by bulging said door centrally against said frame to make it assume the frame contour.
2. In a silo, a door frame, a flexible door, 30 and means for forcing said door into engagement with said frame to make it assume the frame contour by a resultant pulling action from the edges of the door outwardly and toward the center of the door.
3. In a silo, a transversely curved door frame, a flexible door, a truss bar engaging said door at opposite longitudinal edges, and means operating between said truss and said frame at a point intermediate the ends 40 of the truss for pulling it toward said frame to make the door assume the shape of the frame.
4. In a silo, an outwardly curved door frame, a flexible door adapted to be correspondingly curved against the inside of the frame, and locking means located outside the silo arranged to draw said door from

adjacent its edges to bulge it outwardly against its frame to make it assume the contour of the frame.

5. In a silo, a door frame, a flexible door adapted to fit against the inside of said frame, and locking means located outside the silo arranged to draw said door from adjacent its edges outwardly at an angle toward its center against its frame to make it assume the contour of the frame.

6. In a silo, an outwardly curved door frame, a flexible door adapted to be correspondingly curved against the inside of the frame, vertically arranged reinforcing members located adjacent the side edges of said door, and spaced adjustable locking means anchored in said members at one end and effective to pull at an outwardly directed angle to make said door bulge centrally to assume the contour of its frame.

7. In a silo, a vertically extending door frame curved transversely, a flexible door slightly larger than the opening in said frame, clips spaced along the vertical edges of said door, a truss bar adjacent the upper and lower edges of said door each connected with said clips, and means operating between each truss intermediate its ends and said frame for pulling said trusses outwardly.

8. In a silo, a vertically extending door frame curved transversely, a flexible door slightly larger than the opening in said frame, clips along the vertical edges of said door, a truss bar adjacent the upper and lower edges of said door each connected with said clips, and a screw threaded into each truss bar intermediate its ends from said frame to draw said door against said frame.

In testimony whereof I affix my signature in presence of two witnesses.

GEORGE P. PIERCE.
